(57) **CLAIM**

We claim the ornamental design for a cleaning device, as shown and described.

DESCRIPTION

FIG. 1 is a top isometric view of a cleaning device.
FIG. 2 is a bottom isometric view of the cleaning device of FIG. 1.

FIG. 3 is a rear elevation view of the cleaning device of FIG. 1.

FIG. 4 is a front elevation view of the cleaning device of FIG. 1.

FIG. 5 is a right side elevation view of the cleaning device of FIG. 1.

FIG. 6 is a left side elevation view of the cleaning device of FIG. 1.

FIG. 7 is a top plan view of the cleaning device of FIG. 1; and,

FIG. 8 is a bottom plan view of the cleaning device of FIG. 1.

The broken lines in the drawings depict portions of the cleaning device that form no part of the claimed design.

1 Claim, 6 Drawing Sheets
